UNITED STATES PATENT OFFICE

2,473,829

REPEAT DEVICE FOR AUTOMATIC PHONOGRAHS

Sven A. Stolberg, Chicago, Ill., assignor, by mesne assignments, to Raytheon Manufacturing Company, Newton, Mass., a corporation of Delaware

Application April 23, 1945, Serial No. 589,756

5 Claims. (Cl. 274—10)

The present invention relates to improvements in record-changing phonographs, and the like, especially of that type in which the records are automatically released from the bottom of a stack supported above the turntable. Such release is effected by a slight projection of a finger or lug inwardly towards the turntable center-post, such finger pressing against the edge of the lowermost record of the stack to release the record from a shoulder on the center-post, by which shoulder the records are supported. Such general schemes for record release are well known in this art, and one embodiment of such scheme is disclosed in my co-pending application for Letters Patent for improvements in Record-changing phonographs, and the like, Serial No. 576,202, filed February 5, 1945, and assigned to the same assignee as the present application.

In the disclosure of that co-pending application the inward movements of the finger or lug are effected by reciprocation of a vertically extending rock-arm which extends up through the stand which carries the lug or finger itself. These reciprocations are effected in turn by spring force transmitted to the rock-arm, which rock-arm is released when the record release is to occur; and this release of the rock-arm is controlled by the movement of the control cam which determines the cyclic sequence of the various operations incident to record change. Due to the fact that the actual reciprocation of the rock-arm is effected by spring force when such rock-arm is released, it follows that by blocking the rock-arm the reciprocation is prevented, and the inward movement of the record feeding finger or lug is prevented; and thus "repeating" of the playing of the record previously played is effected.

In said application, Serial No. 576,202 referred to above I have disclosed means for blocking the movement of the rock-arm to effect "repeating," and when so blocked the other parts which act under cam operation are permitted to function without interference due to such blocking, by reason of the fact that the movement of the rock-arm is normally effected by spring force when the rock-arm release device functions. The blocking device of said earlier application includes a rotatable or rockable element in the stand which when in one normal position does not interfere with the rock-arm swings, but when in a turned position does effect the desired interference.

The present invention concerns itself especially with a different means for effecting the blocking of the rock-arm for repeat purposes; and comprises generically a device which may be shifted

up and down with respect to the stand, and with respect to the rock-arm itself. When this device is in one position it does not interfere with the rocking of the rock-arm; and when in another position this device blocks the rock-arm movements. One feature of my present invention relates to this blocking device and to the manner in which it is mounted or supported on the rock-arm element.

Sometimes it is desirable to provide a presser arm or device on the upper portion of the stand, which presser arm when in one position exerts a spring pressure of desired amount on the top record of the unplayed stack, and additionally controls the smooth feeding and delivery of the records to the stack on the turntable. This presser arm may be swung up and outwardly away from the stack of unplayed records, or from the top face of the stand, to facilitate removal of played records, or placement of fresh records into the record player. Since this presser arm lies over the upper end of the stand when said presser arm is in working position, the blocking device whereby "repeating" is effected must bear such a relation to this presser arm that there will be no improper interference between these two parts in any position of either of them; and this is a further feature and object of my present invention.

Other features and objects of the present invention will appear from a detailed description of the same, which consists in the features of construction, and combinations of parts hereinafter described and claimed.

In the drawings:

Figure 1 shows a plan view of a typical record-changer phonograph, provided with a stand in one corner for supporting the edge portions of the stack of unplayed records, the central portions of the records of such stack being supported by the shoulder on the center-post; and this figure shows the presser arm provided with an opening through which the blocking device extends upwardly for convenient manipulation;

Figure 2 shows a plan view taken below the plane of Figure 1, and it shows the principal operative parts which effect reciprocation of the rock-arm for record feeding, the edge flange of the turntable being shown partially in section;

Figure 3 shows an elevation of the corner post which supports and feeds the edge portions of the unplayed records; this figure being on enlarged scale as compared to Figures 1 and 2; and Figure 3 being a view looking directly back from the front face of the rectangular housing of the record

changer, so that Figure 3 shows the post actually in 45 degree perspective;

Figure 4 shows an elevation of the corner post at 45 degrees with respect to the view of Figure 3, the upper portion of the post and certain parts, being shown in section;

Figure 5 shows a plan view of the post assembly, on enlarged scale as compared to Figure 1, the presser plate being in lowered or normal position;

Figure 6 shows a bottom or inverted view corresponding to Figure 5;

Figure 7 shows a detailed fragmentary section on the line 7—7 of Figure 8, looking in the direction of the arrows; and

Figure 8 illustrates the action of certain members of Figure 4.

By way of illustration the turntable is shown at 10 in Figure 1, and its downwardly extending flange is shown at 11 in Figure 2. The tone arm 12 is shown as being pivoted to swing about the vertical axis 13 (Figures 1 and 2), and raising and lowering of the tone arm are effected by rising and lowering movements of the pin 14 (see Figure 2). The one-cycle cam is shown at 15, rotating on the vertical axis 16; and turntable drive is effected by the friction drive from the motor shaft 17 to the idler wheel 18, and thence to the turntable flange 11. Cyclic operation of the cam 15 may be effected by the friction wheel chain including the friction wheels 19 and 20, the wheel 19 being carried by the swinging arm 21 so that said wheel may be brought to bear against the friction wheel 18; and the axis 22 of the wheel 20 carrying a pinion which will drive a suitable gear on the periphery of the cam element 15. Release of such one-cycle drive is effected by the shouldered cam 23 carried by the axis 16, said shouldered cam serving to engage a pin 24 which will draw the arm 21 over at completion of the one-cycle rotation, thus withdrawing the friction wheel 19 from the wheel 18. The details of such a drive are disclosed in my co-pending application, Serial No. 576,202, mentioned above, and need not be further described here.

The one-cycle cam 15 carries a pin or stud 25 so that said stud makes one revolution about the axis 16 during the one-cycle movement of the parts.

Concentric with the turntable axis is the up-standing center pin 26 which is provided with the shoulder 27 on which the central portion of the lowermost record of the unplayed stack rests prior to release of such lowermost record for descent to the top of the played records resting on the turntable. Normally such lowermost unplayed record is slightly eccentrically supported with respect to the turntable axis, so that such support on said shoulder 27 will be effected; and when it is desired to release such lowermost record, said record is shifted slightly by pressure against its edge to move it into concentricity with the turntable centerpost. Furthermore the edge portion of such lowermost unplayed record is normally supported so that it will remain properly in position above the stack of records on the turntable and without interference with such turntable stack. Such edge support is effected by the stand, and the slight lateral shift for record feed is effected by means carried by or constituting a portion of such stand. Reference to Figures 3, 4, 5, 6 and 7 shows the details of construction of this stand and its parts.

Conveniently the stand or vertical post comprises a hollow slightly tapered body 28 of suit-

able external design, and which stand is secured to the top face of the housing 29 by means of screws 30 reaching up through said top face into suitable sockets 31 in the lower portion of the stand. To the top of this housing is secured a plate 32 which has the slotted or grooved depression 33 extending radially with respect to the axis of turntable rotation. Within this groove there is placed the finger or lug 34 which may therefore be reciprocated radially a sufficient distance to effect the necessary displacement of the bottom record of the unplayed stack to cause said record to be shifted from support and allowed to descend to the top of the stack of played records supported on the turntable. This finger or lug is held in place in said depression by means of the elements 35 which have their edge portions slightly overlying the edges of the finger or lug in manner similar to that disclosed in my aforesaid co-pending application, Serial No. 576,202.

The top plate 32 is also provided with the side extensions 36 and 37 upon which the edge of the lowermost unplayed record rests, so that the slight inward displacement effected by the inward radial movement of the finger 34 will shift the record's edge away from these projections and permit record descent. It is of course noted that the finger 34 lies in planar alignment with the edge of the record so that it is able to perform its function.

Extending vertically through the body 28 of the stand is the rock-arm 38. This rock-arm is pivoted for rocking movement on the transverse pin 39 extending into the walls of the stand about midway of its height. This rock-arm reaches down through a slot 40 in the housing 29 to a position where it may be engaged by one arm 41 of a bell-crank 42 pivoted at 43 to the housing. The other arm 44 of said bell-crank is normally drawn back against a stop pin 45 carried by the housing, by means of a spring 46, so that when said spring is permitted to effect such complete movement to bring the arm 44 against the stop pin 45, the rock-arm 38 is swung to move its lower end its maximum distance towards the axis of rotation of the cam element 15. Said cam element 15 carries the stud 25 which at the proper time in the cyclic rotation of the cam serves to swing the bell-crank 42 against the force of the spring 46, thus carrying the arm 41 of the bell-crank out far enough to permit swinging of the rock-arm 38 sufficiently to ensure the record feed presently to be described. A spring 47 connects the bell-crank arm 41 to the lower end of the rock-arm 38, so that normally said rock-arm 38 will follow the swing of the bell-crank arm and effect a record feed; but in case the rock-arm 38 should be blocked against swinging, as by the means to be presently described, the bell-crank can nevertheless rock under impulse of the stud 25 without damage, the spring 47 extending, but no record feeding action occurring.

The upper portion of the rock-arm 38 extends through a suitable opening of the finger 34 so that swinging or pivotal movement of the rock-arm is properly communicated to such finger for feeding purposes. Likewise blocking of the rock-arm effects locking of said finger against radial movement.

Slidably mounted on the upper portion of the rock-arm 38 is the finger piece 48. This finger piece conveniently comprises a molded unit having molded therein the L-shaped member 49 so that said member 49 rises and falls with the fin-

ger piece. This member 49 has its horizontal leg 50 adapted to move back and forth free of obstruction when the finger piece is in lowered position (as shown in Figure 4); but by raising said finger piece slightly said lug is brought to an elevation where it will lock against a projection or stop surface 51 of the top plate 32 to prevent feeding movement of the rock-arm; it being noted that when the rock-arm is in normal or non-feeding position (as shown in Figure 4) said finger piece can be raised to the elevation shown in Figure 8, said leg 50 rising to a position directly behind said stop surface 51, so that thereafter, and as long as the finger piece is in such raised position, the rock-arm is blocked against rocking movements. Then, when so locked, any rotation of the one-cycle cam will cause the bell-crank arm 41 to swing, but the spring 47 will yield and allow the rock-arm to remain unrocked and without any record feed.

A spring of leaf type 52 is inserted between the upper portion of the rock-arm and the socket of the finger piece behind the L-shaped element 49 to ensure sufficient friction between the finger piece and the rock-arm so that said finger piece will remain in raised position when once so raised. Conveniently said finger piece is marked to indicate its function, as shown in Figure 3.

The top plate 32 is provided with a pair of up-standing ears 53 and 54 to which is pivoted a presser plate 55 which has the finger 56 extending radially inwardly towards the axis of the turntable; and said finger is provided with the yieldable or soft lug 57 which presses against the top surface of the top record of the unplayed stack of records. Said presser plate has the limit heel 58 which will engage the upper rear portion of the stand or the top plate when the presser plate is fully rocked over as shown by the arrows in Figure 4; but it will be noted that when so raised and swung over, this presser plate completely exposes the upper portion of the stand. A slot 59 is provided in said presser plate to accommodate the finger piece 48, said slot being long enough to allow for full raising movement of the presser plate without interference from the finger piece, even when said finger piece is fully raised to block the record feeding operation.

A spring 60 is provided for exerting a suitable amount of spring pressure on the presser plate to normally hold said plate in the position shown in Figure 4; but when said presser plate is fully raised, said spring will act to retain the presser plate in such raised position, the spring being so connected to the presser plate, and being so supported by the top plate of the stand, that said spring acts with a toggle action, reversing its force as the presser plate is moved past the dead center position of the spring.

I claim:

1. In a record changing phonograph, a turntable, a centering pin extending upwardly from said turntable including a shoulder to support a record eccentrically on said centering pin above said turntable, means for shifting said record laterally to bring it into concentricity with said centering pin and to release said record from said shoulder so it may fall onto said turntable comprising a vertical post adjacent said turntable, means on the upper portion of said post to support the peripheral edge portion of said record when said record is eccentrically mounted on said centering pin and supported on said shoulder, said last-mentioned means being of such a size and positioned so as to be free of said record when

said record is shifted laterally so as to be concentric with said centering pin, a finger positioned at the upper portion of said post and movable on a radial line interconnecting said centering pin and said post, said finger being adapted to engage the peripheral edge of said record and move said record in a direction to release it from said shoulder, movable means associated with said finger for positively moving said finger radially outward from said centering pin, yieldable means tending to move said finger in the other direction, means for effecting movement of said movable means during a record changing cycle of said phonograph, and manually operable means for blocking movement of said finger radially inward toward said centering pin regardless of the movement of said movable means comprising a member movable in a direction substantially parallel with the axis of said post.

2. In a record changing phonograph, a turntable, a centering pin extending upwardly from said turntable including a shoulder to support a record eccentrically on said centering pin above said turntable, means for shifting said record laterally to bring it into concentricity with said centering pin and to release said record from said shoulder so it may fall onto said turntable comprising a vertical post adjacent said turntable, means on the upper portion of said post to support the peripheral edge portion of said record when said record is eccentrically mounted on said centering pin and supported on said shoulder, said last-mentioned means being of such a size and positioned so as to be free of said record when said record is shifted laterally so as to be concentric with said centering pin, a finger positioned at the upper portion of said post and movable along a radial line interconnecting said centering pin and said post, said finger being adapted to engage the peripheral edge of said record and move said record in a direction to release it from said shoulder, a lever associated with said finger disposed within said post and extending in a direction generally parallel with the axis of said post, means for positively moving said lever to cause said finger to move radially outward from said centering pin, yieldable means tending to move said lever and said finger in the other direction, said means for positively moving said lever being operative during a record changing cycle of said phonograph, and manually operable means for blocking movement of said finger radially inward toward said centering pin regardless of the movement of said means for positively moving said lever comprising a member slidably mounted on the upper end of said lever.

3. In a record changing phonograph, a turntable, a centering pin extending upwardly from said turntable including a shoulder to support a record eccentrically on said centering pin above said turntable, means for shifting said record laterally to bring it into concentricity with said centering pin and to release said record from said shoulder so it may fall onto said turntable comprising a vertical post adjacent said turntable, means on the upper portion of said post to support the peripheral edge portion of said record when said record is eccentrically mounted on said centering pin and supported on said shoulder, said last-mentioned means being of such a size and positioned so as to be free of said record when said record is shifted laterally so as to be concentric with said centering pin, a presser arm pivotally mounted on said post and

having an opening therein, a finger positioned at the upper portion of said post and movable on a radial line interconnecting said centering pin and said post, said finger being adapted to engage the peripheral edge of said record and move said record in a direction to release it from said shoulder, movable means associated with said finger for positively moving said finger radially outward from said centering pin, yieldable means tending to move said finger in the other direction, means for effecting movement of said movable means during a record changing cycle of said phonograph, and manually operable means for blocking movement of said finger radially inward toward said centering pin regardless of the movement of said movable means comprising a member extending through said opening in said presser arm and movable in a direction substantially parallel with the axis of said post.

4. In a record changing phonograph, a turntable, a centering pin extending upwardly from said turntable including a shoulder to support a record eccentrically on said centering pin above said turntable, means for shifting said record laterally to bring it into concentricity with said centering pin and to release said record from said shoulder so it may fall onto said turntable comprising a vertical post adjacent said turntable, means on the upper portion of said post to support the peripheral edge portion of said record when said record is eccentrically mounted on said centering pin and supported on said shoulder, said last-mentioned means being of such a size and positioned so as to be free of said record when said record is shifted laterally so as to be concentric with said centering pin, a finger positioned at the upper portion of said post and movable along a radial line interconnecting said centering pin and said post, said finger being adapted to engage the peripheral edge of said record and move said record in a direction to release it from said shoulder, a lever associated with said finger disposed within said post and extending in a direction generally parallel with the axis of said post, means for positively moving said lever to cause said finger to move radially outward from said centering pin, yieldable means tending to move said lever and said finger in the other direction, said means for positively moving said lever being operative during a record changing cycle of said phonograph, and manually operable means slidably mounted on the upper end of said lever including an L-shaped member adapted to cooperate with said

post to block the operation of said finger and lever when said L-shaped member is in a predetermined position whereby the phonograph operates to repeat the playing of the record on said turntable.

5. In a record changing phonograph, a turntable, a centering pin extending upwardly from said turntable including a shoulder to support a record eccentrically on said centering pin above said turntable, means for shifting said record laterally to bring it into concentricity with said centering pin and to release said record from said shoulder so it may fall onto said turntable comprising a vertical post adjacent said turntable, means on the upper portion of said post to support the peripheral edge portion of said record when said record is eccentrically mounted on said centering pin and supported on said shoulder, said last-mentioned means being of such a size and positioned so as to be free of said record when said record is shifted laterally so as to be concentric with said centering pin, a finger positioned at the upper portion of said post and movable along a radial line interconnecting said centering pin and said post, said finger being adapted to engage the peripheral edge of said record and move said record in a direction to release it from said shoulder, a lever associated with said finger disposed within said post and extending in a direction generally parallel with the axis of said post, means for positively moving said lever to cause said finger to move radially outward from said centering pin, yieldable means tending to move said lever and said finger in the other direction, said means for positively moving said lever being operative during a record changing cycle of said phonograph, a molded manually operable finger piece slidably mounted on the upper end of said lever, and an L-shaped member fastened to said finger piece which when in one predetermined position blocks the movement of said lever and finger to cause said record to move onto said turntable.
